The ornamental design for fertilizing material container for lawn and garden, as shown and described.

DESCRIPTION

FIG. 1 is a front elevational view of a fertilizing material container for lawn and garden, showing my new design; the rear elevational view being a mirror image thereof;

FIG. 2 is a left side elevational view of the fertilizing material container for lawn and garden shown in FIG. 1; the right side elevational view being a mirror image thereof;

FIG. 3 is a top view of the fertilizing material container for lawn and garden shown in FIG. 1; and,

FIG. 4 is a bottom view of the fertilizing material container for lawn and garden shown in FIG. 1.
